UNITED STATES PATENT OFFICE.

EDWARD J. WALSH, WILLIAM KEEGAN, AND PATRICK FINUCAN, OF CLEVELAND, OHIO.

DESIGN FOR A SEAL, &c.

SPECIFICATION forming part of Design No. 23,410, dated July 3, 1894.

Application filed December 4, 1893. Serial No. 492,779. Term of patent 14 years.

To all whom it may concern:

Be it known that we, EDWARD J. WALSH, WILLIAM KEEGAN, and PATRICK FINUCAN, citizens of the United States of America, residing at Cleveland, in the county of Cuyahoga and State of Ohio, have invented and produced a new and original Design for Seals or Stamps, of which the following is a specification, reference being had for illustration to the accompanying drawing, that exhibits a plan view of the face of the seal or stamp.

The leading feature of our design consists in a diamond-shape figure, X, having located within it a figure, as at S, representing a horse-shoe.

What we claim is—

The design for a seal or stamp herein shown and described, consisting of a diamond-shape figure, and a figure representing a horse-shoe located within the diamond-shape figure. 20

In testimony whereof we sign this specification, in the presence of two witnesses, this 18th day of November, 1893.

EDWARD J. WALSH.
WILLIAM KEEGAN.
PATRICK FINUCAN.
